MAKING AND PACKAGING STRANDS OF MATERIAL

Howard W. Collins, Newark, Ohio, assignor to Owens-Corning Fiberglas Corporation, a corporation of Delaware

Application September 23, 1942, Serial No. 459,460

14 Claims. (Cl. 242—42)

This invention relates to a method and apparatus for manufacturing and packaging strands of material and also contemplates an improved package of strands.

Although it will be apparent as this description proceeds that my invention is not limited to the production and packaging of strands of any particular kind of material, for the purpose of illustration I have shown my invention as applicable to the manufacture of strands of filaments formed of glass or equivalent inorganic materials.

In the manufacture of strands or filaments of the above general type, a plurality of streams of the selected material flow from a bushing having a given number of small orifices and the streams thus formed are attenuated into filaments by suitable means and the filaments gathered together into a single strand. The strand resulting from the above is usually wound into a package on a revolute supporting member, which may be also the attenuating means, by traversing the strand along the member. This process is disclosed, for instance, in the Fisher Patent No. 2,224,149 of December 10, 1940.

In the production of packaged strands of glass filaments by the above process, and also in the packaging of strands of continuous filaments of other material, the strand of filaments may separate when being unwound from the package especially when there are a few broken filaments in the strand. One or more of the filaments that break away from the strand do not unwind with the strand and form what are called "ringers" on the package. These "ringers" tangle and snarl the windings and interfere with further unwinding of the strand, and, because of the very small diameter of the individual filaments, are extremely difficult to trace and remove, making it necessary oftentimes to discard a large portion of the package as a loss.

It is an object of the present invention to provide a package of strands from which "ringers" are automatically removed in the unwinding operation. This is attained by winding a plurality of strands into a single package in such a manner that each of the strands in unwinding removes any "ringers" left by the other strand or strands. This novel winding also facilitates starting of unwinding since if one end is found and unwound it will start the other end or ends to unwind.

In the attenuation and winding of glass filament strands by the process referred to, the rate of production or the yardage produced from any one bushing is limited to a great extent by the rate at which the strand issuing from the bushing

5 is capable of being packaged or wound on the revolute member. It follows, therefore, that in order to double the production at any one station it was necessary to duplicate all of the apparatus at this station including the traversing equipment. This procedure is not only expensive but requires considerable floor space and necessitates providing additional operators.

10 The present invention contemplates materially increasing the production at any one station without duplicating the equipment by arranging the streams issuing from a single large bushing or from a plurality of separate bushings into a plurality of strands and by simultaneously winding the strands on a single revolute supporting member.

Another object of this invention is to individually wind the strands on the supporting member in spaced relationship so that the windings of the 15 individual strands are, in effect, independent of one another and may be removed individually from the revolute supporting member.

Still another object of this invention is to provide a traversing element having projections successively engageable with the strands to advance the latter lengthwise of the revolute member and having the leading edges of the projections inclined in a direction to maintain the strands in spaced relation during the traversing movement.

20 A further object of this invention is to collect the streams issuing from the bushing orifices into individual strands by pads or guides so positioned with respect to the revolute member to effect return travel of the strands in an out of phase relationship during the interval provided between engagement of the strands by adjacent projections on the traversing element.

25 The foregoing, as well as other objects, will be made more apparent as this description proceeds, especially when considered in connection with the accompanying drawings, wherein:

Figure 1 is a diagrammatic side elevational view of a strand or filament producing apparatus constructed in accordance with my invention;

Figure 2 is a front view of the apparatus of Figure 1;

Figure 3 is a diagrammatic plan view of the apparatus shown in Figures 1 and 2 with the exception of the bushing or feeder; and

Figure 4 is a diagrammatic plan view of a portion of the traversing equipment and of a package wound in accordance with the present invention.

As previously stated, the present invention is illustrated in connection with the manufacture of continuous strands of filaments of inorganic

materials, such as glass or other materials having characteristics similar to glass, and is principally concerned with winding an improved package of the strands and increasing the production of strands with the minimum amount of equipment.

With the above in view reference will now be made to Figures 1 and 2 of the drawings wherein the reference character 10 indicates a bushing having laterally spaced rows of orifices 11 through which molten glass is caused to flow continuously in the form of streams 12. The streams 12 are attenuated to form filaments and the filaments are gathered into individual strands 13 and 14 by suitable collecting guides 15 and 16 respectively. In the present instance, the guides may include sizing pads which function to apply a suitable lubricant to the surfaces of the glass filaments and thereby protect the surfaces of the filaments and bind each group of filaments into an integral strand.

The strands 13 and 14 are simultaneously wound on a revolvable member 17 in the form of a spool supported in any suitable manner for rotation about an axis 18. As a result of winding the two strands on the spool in accordance with the present invention, a package 19 is formed having two individual windings of strands which are capable of being removed as separate strands or, if desired, as one strand from the spool. In the further processing of the strands the two ends from one package may be twisted singly to form two yarns or twisted together to form a yarn of greater size.

In the present instance, the strands are advanced lengthwise of the spool 17 from the end 20 of the spool to the end 21 by a traversing disk 22 supported for rotation about an axis perpendicular to the axis of rotation of the spool and having a plurality of circumferentially spaced projections in the form of pins 23 extending from the periphery thereof. The traversing disk is so located with respect to the spool 17 that the pins 23 respectively engage both strands and move the same from the end 20 of the spool to the opposite end 21 of the latter. It will, of course, be understood that the strands are released from their respective pins at points adjacent the end 21 of the spool 17 and are returned to the end 20 before the next adjacent pin engages the strands. This return movement is effected by positioning the guides or pads 15 and 16 outside the space bounded by planes normal to the axis of rotation of the spool and passing through the ends 20, 21 of the spool or the ends of the package to be wound on the spool. The arrangement is such that when the strands approach the end 21 of the spool they are under tension and will return toward the end 20 as soon as they are released due to their tendency to meet the spool axis at a right angle.

It will be noted from the drawings that the pins 23 are preferably inclined from the periphery of the disk 22 in a direction opposite the direction of rotation of the disk. This disposition of the pins 23 is preferred because it tends to maintain the strands in spaced relationship during traversing movement of the strands by the pins, due to the angular relation between the pins and the surface of the package on the spool and the relation of the package and pads illustrated in Figure 3.

The fact that the pads 15 and 16 are offset from one another in the direction of the axis 18 of the spool 17 causes the strand coming from the

farthest removed pad 15 to traverse along the package at a higher rate than the strand from the other and nearer pad 16 so that during return traverse the strands are out of phase.

5 By the invention two continuous strands are wound on a single spool in spaced and out-of-phase relationship in such a manner that the strands may be readily and separately removed from the spool when desired. This permits the 10 production from a plurality of bushings to be simultaneously wound on a single spool by single traversing equipment. In other words, the present invention renders it possible to at least double the production without increasing the number of machines or stations and without proportionately increasing the number of operators required.

Figure 4 illustrates diagrammatically the type of package wound in accordance with the present invention, and the relation thereto of a portion of the traversing apparatus. The size and spacing of the strands is exaggerated to more clearly illustrate the arrangement thereof on the package. The cycle of winding depicted in this view begins at the point *a* and under action of the traversing disk the two strands 13 and 14 are spiraled about the package to the point *b*, with the strands in spaced relation due to the inclination of the strand-engaging projections on the disk. The strands gradually approach each other as they are traversed along the package due to the change in angular relation between the pins 23 and the package as the pins move along the package so that the strands are wound on the package in out-of-phase relationship. 25 Depending upon the degree of inclination of the pins, the strands may come into actual contact at the end 21 of the package or may be slightly spaced or may cross each other. At the point *b*, the strands are released from the projections on 30 the disk and return along the package under the influence of the offset relation of the guides 15 and 16. Due to the greater distance that one of the guides, namely the guide 15, is spaced outwardly from the plane passing through the end 35 of the package, the strand 13 traverses along the package at a higher rate. This causes the space between the strands to increase as the strands approach the starting position on the package, so that in effect the strands on return 40 traverse are also in out-of-phase relationship.

From the fact that the strands come into contact or even cross each other at the end 21 of the package it can be seen that if substantially radially extending pins are employed in place of the pins 23 on the disk, the strands during the 45 whole of the traversing movement under action of the pins will be in contacting relation and may even cross back and forth over each other and will, in effect, be wound on as a single strand. Although this arrangement of the strands is not as desirable as where traversing is effected by sharply inclined pins, it does, however, result in a package from which two separate strands may be removed if the present invention is followed in obtaining return traverse in out-of-phase relationship.

Regardless of whether the strands wound on under action of the pins, or other traversing mechanism that may be employed, are in spaced, contacting, or crossing relation, the herein disclosed relation of the guides 15 and 16 causes the strands to wind on separately on return traverse. Thus, at least half of the winding is in the form of two separate strands and the ends

may be readily found in the unwinding operation.

Although the invention has been described in connection with the simultaneous production and packaging of double strands, various aspects of the invention are applicable also to the winding or rewinding of previously formed yarns or strands, and also to the production and/or winding of more than two strands. The invention also contemplates that the guides 15, 16 may be replaced by sources of strands, for instance, spools of strands to be rewound into a double end package where aspects of the present invention are employed in the rewinding art.

These and various other modifications may be made within the spirit and scope of the appended claims.

I claim:

1. In apparatus for manufacturing continuous strands of material, a revolute member about which a plurality of lengths of strands are adapted to be found, means for traversing the revolute member with the strands comprising an element rotatable about an axis perpendicular to the axis of rotation of said member and having a plurality of circumferentially spaced projections successively engageable with the strands to move the same in one direction lengthwise of the revolute member, said projections having the leading edges inclined at such angle to the path of traversing movement that the strands are maintained in spaced relationship during the traversing movement and are separately wound in out-of-phase relationship on the revolute member.

2. In apparatus for manufacturing continuous strands, a revolute member about which a plurality of lengths of strands are adapted to be wound, means for traversing the revolute member with the strands including an element movable in one direction substantially lengthwise of the revolute member and having a projection engageable with the strands, the leading edge of said projection being inclined at such an angle to the path of traversing movement that the strands are maintained in spaced relationship during the traversing movement and are released from the projection at the end of the traversing movement in the direction aforesaid, and guide means engaging the strands in advance of the traversing element and so located with respect to the revolute member to effect return movement of the strands and to maintain the strands in spaced relationship during said return movement.

3. In apparatus for manufacturing continuous strands of material, a revolute member about which a plurality of strands are adapted to be wound, means for traversing the revolute member in one direction with the strands and for maintaining the strands in spaced relationship during the traversing movement to separately wind the strands on the revolute member in out-of-phase relationship, and guide means respectively engageable with the strands in advance of the traversing means and so located with respect to the revolute member to effect return movement of the strands and to maintain the strands in spaced relationship during said return movement.

4. In apparatus for manufacturing continuous strands, a revolute member about which a plurality of lengths of strands are adapted to be wound, means for traversing the revolute member with the strands including an element mov-

able in one direction substantially lengthwise of the revolute member and having projections spaced from each other in the direction of travel of the element for successively engaging the strands, and guide means respectively engageable with the strands in advance of the traversing means and so located with respect to the revolute member to maintain the strands in spaced relationship and to effect a traversing movement of the strands in the opposite direction during the interval provided between successive engagement of the strands by the projections.

5. In apparatus for manufacturing continuous strands, a revolute member about which a plurality of lengths of strands are adapted to be wound, means for traversing the revolute member with the strands including a disk rotatable about an axis perpendicular to the axis of rotation of said member and having a plurality of circumferentially spaced projections successively engageable with the strands to advance the same in one direction lengthwise of the revolute member and to release the strands at different points at the end of the traversing movement in said direction, said projections having the leading edges inclined at such an angle to the path of traversing movement that the strands are maintained in spaced relationship during traversing movement in the direction aforesaid and are thereby separately wound around the revolute member in out-of-phase relationship, and guide means respectively engaging the strands in advance of the traversing means and so located with respect to the revolute member to effect traversing movement of the strands in the opposite direction during the interval provided between successive engagement of the strands by the projections and to maintain the strands in spaced relationship as they are moved in said opposite direction.

6. In apparatus for manufacturing continuous strands, a revolute member about which a plurality of lengths of strands are adapted to be wound, means for traversing the revolute member with the strands including an element movable in one direction substantially lengthwise of the revolute member and having projections spaced from each other in the direction of travel of the element for successively engaging the strands, and laterally spaced guide means respectively engageable with the strands in advance of the traversing means and positioned beyond a plane normal to the axis of the revolute member and including the end of the package approached by the projections on the traversing means.

7. The method of packaging continuous strands of material which comprises simultaneously traversing in one direction a revolute member with a plurality of strands, maintaining said strands in spaced relation during the traversing movement thereof as they are wound, and causing the free return thereof in a different spaced relation.

8. The method of packaging continuous strands of material which comprises simultaneously traversing in one direction a revolute member with a plurality of strands, maintaining said strands in spaced relation during the traversing movement thereof, and causing the free return of said strands in out-of-phase relation to each other while being individually wound on said revolute member.

9. The method of packaging continuous strands of material which comprises simultaneously attenuating and winding a plurality of strands individually in spaced relation on a revolute member by engaging said strands with a movable element, guiding the strands in one direction while

traversing said member, and releasing said strands from said element one after the other for free travel in the opposite direction.

10. The method of packaging continuous strands of material which comprises simultaneously attenuating and winding a plurality of strands individually in spaced relation on a revolute member engaging the strands with a movable element, guiding the strands in one direction while traversing said member, and releasing said strands from said element one after the other whereby said strands return in an out-of-phase relation to each other to permit individual unwinding thereof.

11. The method of packaging continuous strands of material which comprises successively traversing in one direction a revolute member with a plurality of strands in spaced relation from separated sources by engaging said strands with a movable element, and successively releasing said strands from said element for free return in individual out-of-phase relation.

12. The method of winding which comprises traversing a plurality of separate strands in one direction along a package in spaced relation and maintaining the space between the strands sub-

stantially constant throughout the traversing movement in said one direction to wind the strands on the package in substantially parallel spaced relation, and traversing the strands in return direction at individually different speeds, thereby causing the strands to be wound on the package in side by side relation with the space between the strands constantly increasing as the return traverse progresses.

13. A package of strands comprising a supporting member, a plurality of continuous lengths of strands wound on the support in spaced relation, the strands of alternate layers disposed in individually different spacing to permit individual unwinding thereof.

14. A package of strands comprising a supporting member, a plurality of continuous lengths of strands successively wound on the support in spaced relation, the strands of alternate layers being in parallel spaced relation and the strands of the others of said layers being spaced apart a distance progressively increasing from one end to the other of the package to permit individual unwinding thereof.

25

HOWARD W. COLLINS.
